UNITED STATES PATENT OFFICE.

HARRY H. OSGOOD, OF WORCESTER, MASSACHUSETTS, ASSIGNOR, BY MESNE ASSIGNMENTS, TO MILLS WOVEN CARTRIDGE BELT COMPANY, OF WORCESTER, MASSACHUSETTS, A CORPORATION OF MASSACHUSETTS.

EYELETING-MACHINE.

1,319,413.

Specification of Letters Patent.

Patented Oct. 21, 1919.

Application filed September 29, 1917. Serial No. 193,881.

To all whom it may concern:

Be it known that I, HARRY H. Osgood, a citizen of the United States, residing at Worcester, in the county of Worcester, 5 State of Massachusetts, have invented a certain new and useful Improvement in Eyeletting-Machines, of which the following is a specification, reference being had therein to the accompanying drawings.

10 The invention relates to eyeletting machines of the class constructed with provisions for piercing or perforating the work to receive an eyelet or other like fastener, and for setting such eyelet or the like in hole 15 or perforation in the work, with or without the addition of a washer or other complementary fastener-member.

The main object of my invention is to provide a novel and improved combined 20 piercing or perforating and setting machine of the type in which the piercing or perforating of the work is followed by the setting of the eyelet or other fastener with the work remaining impaled upon the piercer or perforator until after the setting operation has 25 been performed. The general aim is to produce a machine providing for easy handling of the work and convenience in the presentation thereof to the piercing and setting devices for the successive operations, and for 30 enabling the operations of piercing the work, supplying an eyelet and a washer or other complementary fastener-member when one is employed, and setting, to be rapidly 35 performed.

One special object of the invention is to facilitate the application of an eyelet or eyeleted fastener-member to the protruding end of the piercer or perforator of a machine of the type just mentioned, after the piercer or perforator has been forced 40 through the work and while it remains engaged therewith. Another is to facilitate the application of a fastener-member to the piercer or perforator prior to the piercing 45 or perforating operation.

The invention is embodied in an eyeletting machine comprising opposite relatively movable supports, one thereof provided with a 50 combined piercer or perforator and set and the other provided with means for coöperating with said piercer or perforator and set in piercing or perforating and setting by successive operations, and a work-backing

which in its normal position covers the 55 piercer or perforator but is positioned automatically to expose the piercer or perforator after the piercing or perforating operation for application of a fastener-member thereto. With the work-backing, adapted to be 60 moved by the work in the piercing or perforating operation to expose the piercer or perforator as just mentioned, is combined means whereby it is latched or locked in the 65 position thereof produced by the piercing or perforating operation, namely, retracted toward the base of the piercer or perforator and with the piercer-point or perforator-point protruding through the work in readiness for application of a fastener-member 70 thereto, as for instance an eyelet, in preparation for a setting operation. This automatic positioning of the work-backing in uncovering position facilitates the application of the eyelet or other fastener-member 75 to the point of the piercer or perforator in preparation for the setting operation.

A feature of the invention consists in automatic means whereby the work-backing is returned to normal position after the setting operation. Specifically, this means preferably consists in means for automatically unlatching or unlocking the work-backing so as to permit the actuating spring or springs in connection with the work-backing to return the latter to its said normal position.

Another feature of the invention consists in so constructing and arranging the parts that in the normal position of the work-backing a fastener-member laid against its surface may be slid over the opening for the combined piercer or perforator and set, and passed into place around the said piercer or perforator.

The accompanying drawings show an 95 illustrative embodiment of the invention.

Figure 1 of the drawings is a front elevation, partly broken away, of the said illustrative embodiment, only a portion of the 100 general machine being shown. In this view the parts are disposed in readiness for a perforating operation.

Fig. 2 is a view in horizontal section on line 2, 2, of Fig. 1, looking downward.

Fig. 3 is a view somewhat similar to Fig. 1 but showing the parts at the conclusion 105 of the piercing operation.

Fig. 4 is a front elevation with the movable head or support elevated and the parts in readiness for a setting operation.

Fig. 5 is a partly sectional side elevation 5 of the parts which are shown in Figs. 1 to 3, with the parts positioned as in Fig. 4.

Fig. 6 is a view in vertical section in the plane indicated by the line 6, 6, in Fig. 5.

Fig. 7 is a sectional view on an enlarged 10 scale of the combined piercer and set showing a washer applied thereto.

1 and 2 are the opposite relatively movable supports of the illustrated embodiment 15 of the features of the invention. In such embodiment the relative movement of the supports with respect to each other is provided for by making one support movable toward and from the other, the latter being 20 fixed. In this instance the lower support 1 is the fixed one, and the upper support 2 is mounted in guides in the fixed head 3 of the machine, in which guides it is adapted to be reciprocated vertically toward and from the 25 said fixed lower support. Means for producing the movement of the upper support toward and from the lower support is not shown, because it forms no part of the invention. In practice, any approved devices or mechanism for producing the said movement may be employed, either in the shape 30 of devices transmitting manual effort for the actuation of the upper support, or in the shape of devices or mechanism applying mechanical power at the will of the operator.

35 The support 1 is provided with the combined piercer and set 4, 4^a, and the support 2 is provided with the means for coöperating with said combined piercer and set in piercing and setting by successive operations. Such means may vary in character 40 in practice. In this instance it comprises a die 5 and a set 6 which, in order that they may be caused to alternate in their coöperation with the said combined piercer and set 4, 4^a, are combined with the movable support 2 in manner enabling them to be presented alternately in working position in the said successive operation.

The die 5 and upper set 6 are centrally 50 bored to receive the piercing-spur 4, and the bore of die 5 is enough larger in diameter than the said spur to receive the portion of the material of the work α , Figs. 3 and 4, which is upturned by the passage of such 55 spur through the thickness of the work. If desired, the piercing-spur may be replaced by a punch adapted to coöperate with the die 5 in punching a hole in the work, in which case provision will be made for the 60 escape of the punchings.

To provide for the alternate presentation 65 of the die 5 and set 6 in working position with reference to the combined piercer and set 4, 4^a, they are mounted upon a carrier (7) which in turn is mounted in connection with

the movable support 2 with capacity for shift or adjustment of such character that in one position of the said carrier the die 5 is presented as in Fig. 1 in position to coact with the piercer-spur in the manner shown 70 in Fig. 3 in order to effect the piercing of the work, while the set 6 is turned into an inoperative position; and that in a second position of the carrier, shown in Figs. 4 and 5, the die 5 occupies an inoperative position while the set 6 is presented in position to coact with the set 4^a of the combined piercer and set in a setting operation.

The construction providing for the adjustability of the carrier, to which reference 80 has just been made, may vary more or less in practice in some cases. One specific feature of the invention, however, consists in providing for the adjustability of the carrier by mounting it pivotally in connection with 85 the lower end of the movable support 2, as shown in the drawings, so as to permit the said carrier to be swung from its position in Figs. 1, 2, and 3 into its position in Figs. 4 and 5, and vice versa.

90 In the drawings the carrier is mounted pivotally upon the lower end of the support 2 by means of its connected rock shaft 8, which latter is fitted to bearings in a U-shaped bearing-piece 9 that is connected 95 with the said support. The die 5 and set 6 project from the carrier 7 at an angle to each other, so that when either thereof is in working position the other thereof is turned into an inoperative position at one side or 100 the other as the case may be. By turning the carrier around the axis of the rock shaft the die and set are brought alternately into position for use. Provision is made for holding the carrier in each of its positions 105 of adjustment. In the present instance this means consists in a contracting spiral spring 10 having one end thereof engaged with a screw 11 projecting from the front of the U-shaped bearing-piece 9, and the other end 110 engaged with a stud 12 projecting eccentrically from a plate 13 connected with one end of the rockshaft 8 and located at the front of the said bearing-piece. This stud 12 is located upon the plate 13 in such angular 115 relations with the die 5 and upper set 6 that in the respective positions of swinging adjustment of the carrier 7 the said stud is located at one side or the other of a line drawn through the axis of the carrier. Consequently, the spring acts contractively 120 in either of such positions of adjustment to keep the upper side of the carrier pressed against the top of the slot occupied by the carrier in the bearing-piece 9. When the 125 carrier is swung into the opposite position, the stud is carried to the other side of the said line, and the spring acts in this position of adjustment to hold the other side of the carrier 7 pressed against the top of the said 130

slot in the bearing-piece. Thus the spring acts with equal efficiency to hold the carrier in either of the adjustment-positions into which it may be turned.

- 5 The work-backing 14 is mounted between the two supports 1 and 2, in a location adjacent the fixed support. In this case it is a spring-supported work-supporting table having a hole 15, Fig. 1, there-
10 through to accommodate the combined piercer and set 4, 4^a, and is mounted in place in connection with the said fixed support, and guided in its movements, by means of pins 16, 16, Figs. 1, 3, and 4, pro-
15 jecting downward from it and working in guide-holes in the said support. It is yield-
ingly sustained in its normal position, as for instance by means of expanding spiral springs 17, 17, shown in dotted lines, occu-
20 pying central chambers in the said pins, and compressed between the upper ends of the said chambers and the lower ends of the said guide-holes. The springs may be combined otherwise with the work-backing in practice.
25 They operate by their expansion to raise the work-backing automatically to its normal position from the lower position shown in Figs. 3, 4, 5.

Normally, the work-backing 14 occupies the position shown in Fig. 1, in which its elevation relative to the piercer-spur is sufficient to enable it to cover the point of the said spur. The hole 15 in the work-backing corresponds closely in size with the size 35 of the set 4^a. In case it is desired to apply a washer γ to the piercer-spur 4 before the piercing operation, this readily may be effected by placing the washer on the top surface of the work-backing and sliding it 40 thereon over the hole 15, whereupon it will drop upon the piercer-spur and descend upon the latter until it rests upon the top of the said 4^a, as in Figs. 1 and 7.

The described relation of the work-backing to the piercer-spur 4 in the normal position of the work-backing enables the work α to be laid upon the upper surface of the work-backing and shifted about thereon until the portion thereof which is to receive the 50 eyelet or other fastener is positioned properly with reference to the piercer-spur, etc. In the use of the machine, when the work has been laid upon the top surface of the work-backing, as in Fig. 1, so as to overlie the hole 15 in the work-backing, and the die 5 is brought down upon the work, the downward pressure of the die upon the work will carry the work and work-backing downward in unison, thereby impaling the work 55 upon the piercer-spur 4 as in Fig. 3, by forcing the work downward upon the piercer-spur so that the latter will pass through the work into the interior of the die; and in addition forcing down the work-backing into 60 a position on a level with the set 4^a at the

base of the piercer-spur 4 as in said figure. In this condition of the parts the point of the piercer-spur projects at the upper side of the work and above the top of the work-
65 backing. By the locking of the work-back-
70 ing in this depressed position it is held from rising as the die is raised from the work, and consequently when the upper support 2 is returned to its elevated position the work-
75 backing remains down around the set 4^a as 75 in Fig. 4, and the point of the piercer-spur stands up above the top of the work-back-
80 ing, rendering it easy for the operator to place an eyelet α , Fig. 4, upon the said point, as in said figure.

The latch or lock which in the present instance constitutes the means for automatically positioning the work-backing in the required relation to leave the point of the piercer-spur exposed above the work after 85 the piercing operation, in readiness for the application of a fastener-member, such for instance as an eyelet, consists in the present instance in a latch 18, Figs. 5 and 6, mounted pivotally in connection with the fixed 90 support 1 and adapted to engage with the work-backing. In this instance the said latch is arranged to engage an edge of a plate 19 attached to the under side of the work-backing at a hole 20, which for convenience, is made in the work-backing to admit the top of the latch.

The latch 18 is spring-actuated to cause it to engage automatically with the work-backing, by means of a contracting spiral 100 spring 21 having one end thereof engaged with a fixed point of attachment 22 in connection with the upright portion of the fixed head 3 of the machine, and the other end thereof engaged with an upright arm 105 23 fixed upon the journal or rock shaft 24 of the latch. This spring in contracting acts to hold the upright arm 23 against a stop 25 projecting from the said upright portion of the fixed head, and thereby keeps 110 the latch in a position to engage with the plate 19 on the work-backing as the work-backing is depressed through the action of the descending die against the work.

In the working of the machine, the latch 115 operates to lock the work-backing in the retracted position of the latter relative to the piercer-spur which is given thereto at the time of the piercing operation, as in Fig. 3, and it holds the work-backing in the said 120 position as in Fig. 4 to facilitate the application of the eyelet or other fastener-member to the piercer-spur above the work, and until the setting operation has been effected.

The automatic means whereby the work-
125 backing 14 is returned to the normal position after the setting operation comprises in this instance, as previously mentioned, means for automatically unlatching or un-
locking the work-backing so as to permit 130

the actuating springs 17, 17, in connection with the work-backing to lift the latter to its normal position. The means for automatically unlatching or unlocking the work-backing consists in a trip 26 moving in unison with the movable support 2. This trip is combined and arranged to coöperate in the descent of the movable support 2 for the setting operation so as through its engagement with the arm 23 fixed on the rockshaft 24 of the latch 18 to swing such latch out of engagement with the plate 19 carried by the work-backing, so as thereby to free the work-backing to the action of its actuating springs 17, 17, which thereupon raise the work-backing to its normal position shown in Fig. 1 covering the piercer-spur 4.

The trip 26 is made inoperative for the stroke of the support 2 for the piercing operation, and made operative for the stroke of said support for the setting operation, by being moved into and out of engagement-relations with the arm 23 of the spring-actuated latch 18. In the illustrated embodiment, the said trip is a projecting portion or extension of the rear end of the rock shaft 8 of the carrier 7 for the die 5 and upper set 6. This extension is eccentrically disposed with relation to the axis 30 of the said rock shaft, so that in one position thereof, namely, that which is assumed by it when the carrier 7 occupies the position shown in Figs. 1, 2 and 3, with the die 5 in position to act and the set 6 turned into an inoperative position at one side, the trip 26 will occupy such a relation with respect to the arm 23 that in the descent of the movable support 2 for the piercing operation the said trip will pass down at one side of the arm 23, without actuating the said arm and latch to disengage the latch from the work-backing; while in the position of the carrier 7 which places the upper set 6 in position to operate for setting purposes and 45 disposes the die 5 at one side in an inoperative position as in Figs. 4 and 5, the trip 26 occupies a position to engage with the arm 23 as the movable support 2 descends for the setting operation, and consequently 50 through such engagement with the said arm the arm will be pressed to one side and the latch will be disengaged from the work-backing.

As soon as the latch in disengaged from the work-backing so as to unlatch or unlock the work-backing, the latter will be raised by the action of its springs 17, 17, and as it is moved upward it will push the work upward so as to disengage it from the piercer-spur 4.

What is claimed as the invention is,—

1. An eyeleting machine comprising opposite relatively movable supports, one thereof provided with a combined piercer or perforator and set and the other provided

with means coöperating with said piercer or perforator and set in piercing or perforating at one working stroke and setting at the succeeding stroke, and a movable work-backing which in its normal position covers the piercer or perforator but between the piercing stroke and the setting stroke automatically exposes the piercer or perforator or for application of a fastener-member thereto.

2. An eyeleting machine comprising opposite relatively movable supports, one provided with a combined piercer and set and the other provided with means coöperating with said piercer and set in piercing and setting by successive operations, a movable work-backing, means whereby after the piercing operation the work-backing is retained in position to expose the piercer-point for convenient application of a fastener-member thereto, and automatic means whereby the work-backing is returned to normal position after the setting operation.

3. An eyeleting machine comprising opposite relatively movable supports, one provided with a combined piercer and set and the other provided with means coöperating with said piercer and set in piercing and setting by successive operations, a work-backing moved by the work in the piercing operation to uncover the piercer, and means whereby the work-backing when relieved from the pressure of said coöperating means is latched temporarily in such condition to provide for the application of an eyelet or other fastener member thereto.

4. An eyeleting machine comprising opposite relatively movable supports, a combined piercer and set mounted on one of said supports, a carrier mounted on the other support, provided with a die to coöperate with the piercer in piercing and a set to coöperate with the first-mentioned set in setting, and adapted to be shifted to present said die and set alternately in working position, a yielding work-backing adjacent said combined piercer and set, and means for latching said work-backing after the piercing operation with the piercer-point protruding through the work in readiness for application of a fastener-member thereto in preparation for the setting operation.

5. An eyeleting machine comprising opposite supports, one movable toward and from the other, a combined piercer and set mounted on one of said supports, a die to coöperate with the piercer in piercing and a set to coöperate with the first-mentioned set in setting, both mounted upon the other support and adapted to be shifted alternately into working position, a movable work-backing, means whereby the work-backing is positioned to expose the piercer-point after the piercing operation for application of a fastener-member thereto, and

means whereby the work-backing is returned to normal position after the setting operation.

6. An eyeleting machine comprising opposite relatively movable supports, one provided with a combined piercer and set and the other with means for coöperating with said piercer and set in piercing and setting by successive operations, a work-backing 5 movable with the work in the piercing operation, means for locking the said work-backing in the position given by the piercing operation, with the piercer-point exposed for application of a fastener-member there- 10 to after the pressure exerted by the piercing operation is relieved, and automatic means whereby the work-backing is released to permit it to return to normal position after the setting operation.
7. An eyeleting machine comprising opposite supports, one movable toward and from the other, a combined piercer and set mounted on one of said supports, a die to coöperate with the piercer in piercing and a 15 set to coöperate with the first mentioned set in setting, both mounted upon the other support and adapted to be shifted alternately into working position, a work-backing 20 movable with the work in the piercing operation, means for locking said work-backing in the position produced by the piercing operation, with the piercer-point exposed for application of a fastener-member thereto, and means acting during the 25 movement for the setting operation to release the work-backing for return to normal position.

8. An eyeleting machine comprising opposite supports, one movable toward and from the other, a combined piercer and set mounted on one of said supports, a carrier 30 mounted on the other support, provided with a die to coöperate in piercing and with a set to coöperate in setting, and adapted 35 to be shifted to present said die and set alternately in working position, a yielding work-backing, means for locking said work-backing with the piercer-point protruding through the work after the piercing operation, and automatic means to release the 40 work-backing for return to normal position after the setting operation.

9. An eyeleting machine comprising opposite supports, one movable toward and from the other, a combined piercer and set mounted on one of said supports, a carrier 45 mounted on the other support, provided with a die to coöperate in piercing and with a set to coöperate in setting and movable to present said die and set alternately in working 50 position, a yielding work-backing, means for locking said work-backing in a retracted position relative to the piercer given thereto by the piercing operation, and 55 normally inoperative unlocking means made

operative by adjustment of said carrier for setting operation to release the work-backing for return to normal position after the setting operation.

10. An eyeleting machine comprising opposite supports relatively movable toward and from each other, a combined piercer and set mounted on one of said supports, a carrier pivoted to the other support, provided with a die to coöperate in piercing and with a 70 set to coöperate in setting disposed in an angular relation to each other, said carrier adapted to be turned to present said die and set alternately in working position, a work-backing 75 movable with the work in the piercing operation, means for locking said work-backing in the position relative to the piercer produced by the piercing operation, and means made operative by the adjustment for setting to release the work-backing 80 for return to normal position after the setting operation.

11. An eyeleting machine comprising opposite supports relatively movable toward and from each other, a combined piercer 90 and set mounted on one of said supports, a carrier pivoted to the other support, provided with a die to coöperate in piercing and with a set to coöperate in setting disposed in an angular relation to each other, said 95 carrier adapted to be turned to present said die and set alternately in working position, a work-backing movable with the work in the piercing operation, means for locking said work-backing in the position relative 100 to the piercer produced by the piercing operation, and normally inoperative means made operative by adjustment of said carrier for the setting operation to release the work-backing in the movement for the setting 105 operation for return to normal position.

12. An eyeleting machine comprising opposite supports relatively movable toward and from each other, a combined piercer and 110 set mounted on one of said supports, a carrier mounted on the other support, provided with a die to coöperate in piercing and with a set to coöperate in setting, and movable to present said die and set alternately in working 115 position, a yielding work-backing, means for locking said work-backing in the position relative to the piercer produced by the piercing operation, and trip connected with said carrier and acting in the movement for the setting to unlock the work-backing to permit it to return to normal position after the setting operation.

13. An eyeleting machine comprising opposite supports relatively movable toward 125 and from each other, a combined piercer and set mounted on one of said supports, a carrier pivoted to the other support, provided with a die to coöperate in piercing and with a set to coöperate in setting dis- 130

6
posed in an angular relation to each other, said carrier adapted to be turned to present said die and set alternately in working position, a movable work-backing, a latch 5 for retaining said work-backing in the position relative to the piercer produced by the piercing operation, and a trip turning in unison with said carrier, given an idle relation when the die is in position for action, 10 and brought into working relation when the set is in position for action to effect disengagement of the latch in the movement of the support on which the carrier is pivoted.

15 14. An eyeleting machine comprising opposite supports relatively movable toward and from each other, a combined piercer and set mounted on one of said supports, a carrier pivotally mounted on the other support, provided with a die to coöperate in piercing and with a set to coöperate in setting, said die and set disposed in an angular

relation to each other and said carrier adapted to be turned to present them alternately in working position, a spring which 25 keeps the carrier in each of its positions of angular adjustment, a movable work-backing, a latch for retaining said work-backing in the position relative to the piercer that is produced by the piercing operation, 30 and a trip turning in unison with said carrier, given an idle relation when the die is in working position and brought into working relation when the set is in working position, to effect disengagement of the latch in the movement of the support on which the turning carrier is mounted.

In testimony whereof I affix my signature in presence of two witnesses.
